Fig. 5. Inventor

Oliver B. Woodrow

by Doug & Roque, Attys.

UNITED STATES PATENT OFFICE.

OLIVER B. WOODROW, OF NEWTON, IOWA.

WRINGER.

Application filed October 15, 1924. Serial No. 743,767.

This invention relates to improvements in wringers for washing machines of that type which is mounted on a vertical support and adapted to swing in a horizontal plane and 5 to be locked and operated in various positions of its swinging movement, and having the power for operating the wringer applied through the said vertical shaft in the form of a rotating vertical shaft. When the 10 power is thus applied, there is considerable tendency for the wringer frame to rotate about the said support on its pivotal axis, due to the torque between the driving members. It often happens that if the mechanism for locking the wringer in its various 15 adjusted positions should be released while the wringer is in gear, the wringer frame will be driven about its pivotal axis, which often results in injury to those operating the 20 machine.

It is, therefore, the object of my invention to provide in connection with a wringer of this type improved locking mechanism, whereby the wringer cannot be swung about 25 its vertical axis until after it has been thrown out of gear, or cannot be thrown in gear until it has been locked.

A further object is to provide means whereby the wringer may be easily and 30 quickly detached from its supporting member so it may be packed in a compact space while being shipped, or for removal for repairs.

My invention consists in the construction, 35 arrangement and combination of the various parts of the device, whereby the objects contemplated are attained, as hereinafter more fully set forth, pointed out in my claims, and illustrated in the accompanying drawings, in which:

Figure 1 is a side elevation of my improved wringer mechanism showing the manner in which it is mounted on the washing machine tub.

Figure 2 is an enlarged detail end elevation of my improved mechanism.

Figure 3 is an enlarged, detail, longitudinal sectional view.

Figure 4 is an end elevation of the reverse gear housing with the end cover plate removed.

Figure 5 is a detail sectional view taken on the line 5—5 of Figure 1.

The numeral 10 indicates a washing machine tub having a base member 11 and supporting legs 12. The said legs 12 are pro-

vided with cross braces 13, one of which is designed to carry a motor platform 14 on which an electric motor 15 is mounted. A horizontally arranged shaft 16 is mounted beneath the tub 10 and provided at one end with a pulley wheel 17 designed to carry a belt wheel 18 operated from the motor 15. The shaft 16 has its opposite end extended into a gear casing 19 located at the bottom 60 and at one side of the tub 10.

The gear casing 19 is provided with an upright tubular support 20, the lower end of which communicates with the interior of gear casing 19. The upper end of the support 20 is provided with a bracket 21 rigidly secured to the upper end of the tub 10. The said bracket 21 is designed to receive the upper end of the tubular member 20, as clearly shown in Figure 3, said bracket 75 being provided with a slotted clamping member 22. A set screw 23 is designed to extend through an opening 24 in the support 20. The upper end of the tubular support 20 is designed to receive a sleeve 25 80 which is formed integral with the cylindrical gear casing 26. The sleeve 25 is provided with an annular groove 27 to receive the inner end of the set screw 23. This provides means whereby the gear casing 26 is 85 easily and quickly removed by simply loosening the set screw 23 and lifting the sleeve vertically from within the tubular support 20.

The gear casing 26 is provided with a 90 bracket member 28 formed cylindrical and has its outer end provided with flanges 29 to which the wringer frame 30 may be secured by means of suitable bolts 31. This provides means whereby the wringer may 95 be swung in a horizontal plane through an angle of 360°.

The member 28 is formed hollow, the outer end of which is provided with a bearing 32 in which the hub 33 of the bevel gear 34 is rotatively mounted. The hub 33 is provided with a stub shaft 35 having its inner end flattened at 36, and designed to rest in a coupling member 37 which makes connection with the wringer shaft 38, said 100 wringer shaft having its outer end flattened at 39. The gear 34 provides means whereby rotation may be imparted to the wringer shaft 38.

The housing 26 is provided with a vertically arranged shaft 40, which extends 110 downwardly through the sleeve 25 and has

at its lower end a coupling member 41, designed to coact with a similar coupling member 42 mounted on the upper end of a vertically arranged shaft 43. The lower end of the shaft 43 extends downwardly into the gear housing 19 and is provided with a bevel gear 44. Said gear 44 is in mesh with a bevel gear 45 on the outer end of the shaft 16. The coupling member 41 is rigidly secured to the shaft 40, while the coupling member 42 is rigidly secured to the shaft 43. The said coupling members are of that type having coacting lugs 46 which are adapted to be disconnected when the sleeve 25 is elevated and removed from the tubular member 20.

The upper end of the shaft 40 is provided with a bevel gear 47 designed to mesh with the upper face of the bevel gear 34. A bevel gear 48 is also mounted on the shaft 40 and designed to mesh with the lower edge of the bevel gear 34. Each of the bevel gears 47 and 48 have their inner faces provided with lugs 49 which are designed to coact with similar lugs 50 on a sliding sleeve 51, which is splined to the shaft 40. The sleeve 51 is provided with an annular groove 52 in which is mounted a block 53. One side of the housing 26 is left open so that the gears 34, 47 and 48 may be inserted. The open end is provided with a cover plate 54 having a hub portion 55 designed to receive a stub shaft 56 which is in alinement with the shaft 35. The inner end of the stub shaft 56 is provided with an enlarged portion 57 in which a crank pin 58 is mounted. Said crank pin is inserted in the block 53 in such a manner that as the shaft 56 is rotated, the sleeve 51 may be elevated and lowered for the purpose of reversing the gear 34, by throwing the lugs 50 of said sleeve into and out of operation with either of the lugs 49 of the gears 47 and 48 in the usual manner.

The shaft 56 is provided with a series of depressions 59 designed to receive a spring actuated pawl 60 so that the shaft may be retained in one of three positions, either with the sleeve 51 at its lower position, or at its upper position, or at a position midway between the two in which case the shaft 40 is in operative relation with neither of the gears 47 or 48, and which I shall term the neutral position.

The outer end of the shaft 56 is provided with a hand lever 61 having a hand knob 62 at its upper end. The hub of the lever 61 is provided with a semi-circular rack 63 provided with a notch 64 diametrically opposite the lever 61. The upper end of the bracket 21 is provided with an annular flange 65, which is also provided with a series of notches 66. The outer face of the cover plate 54 is provided with a pair of lugs 67, between which a latch device 68 is mounted having the form of a bell crank

lever. The horizontal leg of the latch device 68 is designed to enter the notch 64 when the lever 61 is in an upright or neutral position, while the vertical leg 69 is designed to enter the notches 66. The leg 69 is provided with a handle portion 70 by means of which the latch is actuated.

The parts are so arranged that when the leg 69 is in one of the notches 66, it is out of the notch 64, but cannot be moved out of the notch 66 until it has entered the notch 64. This provides means whereby the lever 61 will always have to be moved to a neutral position with the wringer thrown out of gear before the latch device can be released from the notch 66, thereby providing means whereby the wringer is positively held against being moved from one position to another until the wringer mechanism has been thrown out of gear, at which time there is no tendency for the wringer to swing about its pivotal center, due to the driving power of the shaft 43. Likewise the wringer will have to be locked in any one of its swinging positions of movement before the wringer can be set in motion.

By loosening the set screw 23 so that it disengages the groove 27, it will be seen that the wringer may be easily and quickly detached from the support 20 by simply lifting it upwardly, causing the sleeve 25 to be removed from the upper end of the support, the coupling members 41 and 42 disengaging each other.

By providing the clutch member 37 I have provided means whereby the wringer may be easily and quickly attached or detached from the gear housing without the use of keys or pins, which at the same time provides a limited amount of flexibility so that if the stub shaft 35 and the shaft 38 are not in exact alinement, they will be driven without binding either of said shafts.

I claim as my invention:

1. In a device of the class described, a tubular upright support, a gear housing having a downwardly extending sleeve rotatively mounted in the upper end of said support, the outer surface of said sleeve being provided with an annular groove, a bracket for supporting the upper end of said tubular member in fixed relation to the upper end of a washing machine tub, the upper end of said bracket being provided with a circular flange having a series of notches in its periphery and also a set screw for entering the groove of said downwardly extending sleeve to lock said sleeve against longitudinal movement, said bracket including means for clamping the upper end of said tubular member, a shaft extending longitudinally through said sleeve, the lower end of said shaft being provided with a coupling member, a pair of bevel gears spaced apart and rotatively mounted on the upper end of said

- shaft within said housing, a second shaft arranged transversely to the upper end of the first shaft, a bevel gear on said second shaft in mesh with both of the first bevel gears, 5 said housing being provided with means for detachably securing a wringer with one of its roller shafts in alinement with said second shaft, means for detachably connecting said second shaft and said roller shafts, a clutch member splined to said vertical shaft adapted to be moved to upper, lower and neutral positions and adapted to throw one of said bevel gears into gear when in either of its extreme positions of movement, means 10 for moving said clutch member comprising a shaft, means for imparting movement to said clutch member as the shaft is oscillated, a handle on the outer end of said shaft having a segment with a notch, a latch device pivoted to said gear casing having one member 15 designed to engage the notches of said circular flange of said bracket, the parts being so arranged that when the latch is in the notch of said segment it will be out of any of the notches of said flange, or vice versa, the segment being so positioned that when the lever is moved to any other position other than its neutral position the latch will be locked within any one of the notches of 20 said flange.
2. In a device of the class described, a tubular upright support, a gear housing having a downwardly extending sleeve rotatively mounted in the upper end of the said support, a bracket for supporting the upper end of said tubular member adjacent to a washing machine tub, one end of said bracket 25 being provided with a circular flange having a series of notches in its periphery, a shaft extending longitudinally through said sleeve, 40 the lower end of said shaft being provided with a coupling member, a pair of beveled gears spaced apart and rotatively mounted on the upper end of said shaft within said housing, a second shaft arranged transversely to the upper end of the first shaft, a bevel gear on said second shaft in mesh with both of the first bevel gears, said housing being provided with means for detachably securing a wringer with one of its roller shafts in alinement with said second shaft, means for detachably connecting said second shaft and said roller shafts, a clutch member splined to said vertical shaft adapted to be moved to upper, lower and neutral positions and adapted to throw one of said bevel gears into gear when in either of its extreme positions of movement, means for moving said clutch member comprising a shaft, means for imparting movement to said clutch member as the shaft is oscillated, a handle on the outer end of said shaft having a segment with a notch, a latch device pivoted to said gear casing having one member 50 designed to engage the notches of said circular flange of said bracket, the parts being so arranged that when the latch is in the notch of said segment it will be out of any of the notches of said flange, or vice versa, the segment being so positioned that when the lever is moved to any other position other than its neutral position the latch will be locked within any one of the notches of said flange. 55
